ELECTROCARDIOGRAM PLATE ELECTRODE

Arthur J. Hinnekamp, Excelsior, Minn., assignor to
Medical Plastics, Inc., Minnetonka, Minn.

Filed May 22, 1972, Ser. No. 255,963

Term of patent 14 years

Int. Cl. D24—01

U.S. Cl. D83—1 F

FIG. 5

FIG. 4

FIG. 1 is a top plan view of the electrocardiogram plate electrode showing the new design;

FIG. 2 is a side elevational view of the electrode of FIG. 1;

FIG. 3 is a bottom plan view of the electrode of FIG. 1; and

FIG. 4 is an end elevational view of the right side of FIG. 1, the left side being a mirror image.

I claim:

The ornamental design for an electrocardiogram plate electrode, substantially as shown and described.
